BUILDER MECHANISM

Edward Haggerty, Albert O. Roy, and Robert Hargreaves, Whitinsville, Mass., assignors to Whitin Machine Works, Whitinsville, Mass., a corporation of Massachusetts

Application December 30, 1942, Serial No. 470,598

2 Claims. (Cl. 242—43.3)

This invention relates to builder mechanism as commonly used in spinning or twisting machines to control the winding of the yarn and the shaping of the bobbins. Such control is commonly exercised by changing either the length or the locus of the yarn traverse relative to the bobbin.

For certain purposes, it is desirable to produce bobbins of large diameter and having a substantial taper at both the top and the bottom ends of the yarn winding. It is also essential that the yarn be so laid that the windings will always come off singly from the ends of the bobbins and not in bunches.

It is the general object of our invention to provide improved builder mechanism by which such a double taper winding may be conveniently attained.

A further object is to provide mechanism by which this result may be accomplished through the shifting of the locus of the yarn traverse, while maintaining the length thereof substantially constant. In the preferred construction, the locus of the winding is gradually and oppositely shifted, first toward one end of the bobbin, and then toward the other.

A preferred form of our invention is shown in the drawings, in which

Fig. 1 is a plan view of our improved builder mechanism;

Fig. 2 is a side elevation, looking in the direction of the arrow 2 in Fig. 1;

Fig. 3 is an end view, looking in the direction of the arrow 3 in Fig. 2;

Fig. 4 is a partial plan view of an auxiliary builder lever;

Fig. 5 is a partial plan view of a main builder lever and certain associated parts;

Fig. 6 is a detail front elevation, partly in section, along the line 6—6 in Fig. 5 and showing a friction brake device; and

Fig. 7 is a front view of a bobbin as fashioned by our improved builder mechanism.

Referring to the drawings, our improved builder mechanism comprises a main builder lever 10 and an auxiliary builder lever 11, both pivotally mounted on a short shaft 12 which is supported in a fixed bearing bracket 14. The bracket 14 may be clamped to the frame of the spinning or twisting machine, or may be independently supported on a separate floor stand, as may be most convenient.

The main builder lever 10 has an offset projection 16 in which a cam roll 17 is rotatably mounted on a stud 18. The cam roll 17 is in

continuous engagement with the usual heart cam or builder cam 20, shown in Fig. 3 but omitted in Figs. 1 and 2 for the sake of clearness.

The usual outline and position of this heart cam is clearly shown in the prior patent to Hargreaves, No. 1,984,641, issued to applicant's assignees December 18, 1934.

A feed shaft 22 extends lengthwise of the main builder lever 10 and is rotatably supported in suitable bearings therein. A worm 24 is mounted on the shaft 22 and engages a worm gear 26, rotatable on a stud 27 fixed in an upwardly projecting portion 28 of the main lever 10. An auxiliary cam 30 is mounted on the outer end of the shaft 27, to rotate with the worm gear 26. The cam 30 engages an auxiliary cam roll 32, rotatably mounted in a recessed portion of the auxiliary lever 11 (Fig. 4).

A plurality of studs 40 (Fig. 1) are mounted in the lever 11 near its free or swinging end, and a builder chain 42 (Fig. 2) may be attached to any one of the studs 40. By providing a plurality of studs, several different yarn traverse lengths may be obtained from the same main builder or heart cam. A friction brake device 50 (Fig. 6) is preferably provided at the inner end of the feed shaft 22, and friction is applied thereto by a compression spring 51.

A ratchet wheel 55 is mounted on the front end of the feed shaft 22, and a compound feed lever 60 (Fig. 3) is mounted to swing about the axis of the shaft 22. Spring-pressed feed pawls 61 and 62 are mounted on the two arms of the feed lever 60, which arms are relatively adjustable so that the feed pawls 61 and 62 may be relatively set for half-tooth feed if so desired.

A feed rod 70 is pivoted at 71 to one arm of the feed lever 60 and extends upward through a fixed frame member 72. The travel of the rod 70 relative to the fixed member 72 is limited by adjustable upper and lower stop collars 74 and 75.

As the main builder lever swings upward and downward under the control of the builder cam 20, the feed pawls 61 and 62 will be moved clockwise and backward on a return or idle movement as the builder lever moves downward, and will be forced forward or anti-clockwise in a feeding movement as the builder lever swings upward. The extent of the ratchet feed may be adjustably determined by the setting of the stop collars 74 and 75.

The construction and operation of the ratchet feed, and the connection of the builder chain 42 to the vertically movable spindle rail or ring

rail of a spinning or twisting machine form no part of our present invention, and for a more complete description of these features, reference is made to the Hargreaves patent previously cited.

With the slow pick-feed of the ratchet wheel and feed shaft, and with the slow worm-and-worm-gear connection between the feed shaft and the auxiliary cam 30, it will be evident that the cam 30 will be shifted only very slightly for each swinging movement of the main builder lever 10 and for each vertical traverse of the yarn relative to the bobbin. The change in the relative positions of the main builder lever 10 and the auxiliary lever 11 is therefore so slight at each reciprocation of the levers that the traverse of the yarn on the bobbin is substantially constant and is directly controlled by the contour of the main builder or heart cam 20.

Gradual rotation of the auxiliary cam 30, however, effects a slow shifting of the auxiliary lever 11 relative to the main builder lever 10, and this slow shifting effects a corresponding shifting of the locus of the yarn traverse on the bobbin. By varying the contour of the auxiliary cam 30, the shape of the finished bobbin may be changed within wide limits.

A usual type of bobbin is shown in Fig. 7, in which the finished bobbin is tapered at both the upper and lower ends, and in which the yarn package has an over-all length of eight inches while the yarn traverse is shown as about six inches. This involves a two inch shifting of the locus of yarn traverse under the control of the auxiliary cam 30.

By varying the throw and contour of the cam 30, different desired shapes of yarn packages may be readily attained, and by shifting the builder chain 42 from one to the other of the studs 40, a longer or shorter yarn traverse may be produced by the same main builder or heart cam.

It will be noted that all parts of our improved builder lever are of simple and rugged construction and that there is very little about the builder mechanism which can possibly get out of order or cause trouble. Furthermore, the auxiliary cam 30, being on the outer end of the shaft 21, can be readily removed and replaced by a different cam whenever this becomes necessary or advisable.

Having thus described our invention and the advantages thereof, we do not wish to be limited to the details herein disclosed, otherwise than as set forth in the claims, but what we claim is:

1. In a builder mechanism, a main builder lever, an auxiliary builder lever to which a builder chain is connected, said main and auxiliary levers being mounted on a common axis, a main builder cam constantly rotated to give said main builder lever swinging movements of fixed arc and said auxiliary lever being correspondingly swung by and with said main lever, an auxiliary cam rotatably mounted on said main builder lever and effective to give said auxiliary lever an additional swinging movement, a feed shaft rotatably mounted on said main lever and extending longitudinally thereof, a brake device for said feed shaft, a worm and worm gear connection between said feed shaft and said auxiliary cam, and intermittently-operated automatic ratchet feed devices for said feed shaft, located at the free swinging end of said main lever.

2. In a builder mechanism as set forth in claim 1, the feature that the ratchet feed devices comprise two relatively adjustable feed pawls by the joint operation of which a half-tooth feed may be effected.

EDWARD HAGGERTY.

ALBERT O. ROY.

ROBERT HARGREAVES.
